UNITED STATES PATENT OFFICE.

WILLIAM A. SCHLUETER AND ADOLPH SCHILLINGER, OF TULSA, OKLAHOMA.

SAMPLING TOOL.

Application filed December 14, 1925. Serial No. 75,481.

This invention relates to a sampling tool for use in obtaining oil samples from oil tanks or the like.

The object of the invention is to provide a sampling device of this character which may be used to obtain a sample at any depth, which cannot stick or clog, which is easily adjusted, and which may be easily opened when it is desired to take the sample there-

10 from.

A further object resides in the provision of a sampling device of this character and having these advantages and which is of simple and durable construction, reliable 15 and effective in operation and easy and comparatively inexpensive to manufacture.

Other objects and advantages reside in certain novel features of the construction, arrangement and combination of parts which 20 will be hereinafter more fully described and particularly pointed out in the appended claims, reference being had to the accompanying drawings forming a part of this specification, and in which:

25 Figure 1 is a perspective view showing a sampling device constructed in accordance with the present invention,

Figure 2 is a view thereof in vertical section taken approximately on the line 2—2 of

30 Figure 1,

Figure 3 is a bottom plan view showing the closure for the bottom plate in open position,

Figure 4 is a similar view showing the 35 closure in closed position,

Figure 5 is a fragmentary view in elevation looking in the direction of the arrows 5—5 of Figure 4,

Figure 6 is a similar view looking in the 40 direction of the arrows 6—6 in Figure 3,

Figure 7 is a top plan view,

Figure 8 is a view in horizontal cross section on the line 8—8 of Figure 2, and

Figure 9 is a detail sectional view on the 45 line 9—9 of Figure 1.

Referring to the drawings it will be seen that the sampler constituting the present invention includes a hollow body, designated generally at 1, and preferably made up of a 50 hollow cylinder 2 of glass or the like protected by curved guard plates 3 of metal which are held against the glass cylinder by end plates 4 and 5 secured to the guard plates 3 by screws 6. The guard plates have 55 lugs 3^a at their ends which abut the end pieces or heads 4 and 5 and with which the

screws 6 co-act. Elastic packing rings 7 are interposed between the ends of the glass cylinder 2 and the end pieces or heads 4 and 5 as illustrated to advantage in Figure 2. 60 Both of the end pieces 4 and 5 have annular flanges, designated at 8 and 9, respectively, flanges 8 and 9 snugly fitting over the ends of the cylinders as also seen to advantage in Figure 2.

The upper end piece or head 4 is provided with a large central opening 10. The lower end piece or head 5 is provided with a plurality of openings 11 having the approximate form of a sector. A closure is provided for the openings 11 and consists of a plate 12 having a hub 13, closure elements or ribs 14 provided with beveled edges 15 and a peripheral ring 16 provided with outwardly extended inclined lugs 17 and 18. 75 The hub 13, closure ribs 14, peripheral ring 16 and the lugs 17 and 18 are all preferably cast or otherwise suitably formed integral. The hub 13 of the closure is suitably fastened, as at 19, to a pivot shaft 20 rotatably 80 fitted in an opening 21 provided therefor in the lower end piece or head 5. At its upper end the shaft 20 is provided with a flange 22 which is integral therewith or otherwise suitably fixed thereto. A torsional coil spring 23 encircles the shaft 20 above 85 the lower head 5 and has its lower end fastened, as at 24, to the plate 5 and its upper end fastened, as at 26, to the flange 22 of the shaft 20. The spring 23 is not only torsionally tensioned but is under compression 90 to a slight extent so as to resiliently hold the closure plate 12 snugly up against the underside of the lower end plate or head 5 and also maintain this closure plate 12 in 95 such angular position that its ribs or closure elements 14 cover and close the openings 11.

The lugs 17 and 18 afford a convenient means whereby the closure plate 12 may be turned against the tension of the spring 23 100 to move the closure elements or ribs 14 out of registry with the openings 11, thereby opening the lower end of the sampler. Means is provided for releasably holding the closure plate in such open position and consists of a lock rod or holder rod 30 slidably fitted in guide openings provided therefor in lugs 31 on the end pieces 4 and 5. The lower end of the lock rod 30 is beveled, as indicated at 32 (see Fig. 6) and this lower beveled end is engageable with the lug 17 110 to hold the lug and the closure plate 12

in open position. The lock rod 30 is yieldably held in position to engage the lug 17 by means of an expansible coil spring 33 encircling the upper portion of the lock rod 30 5 and abutting the underside of the lug 31 of the end piece or head 4 at one end and a cotter pin 34 carried by the lock rod 30 at its lower end.

In order to trip or release the lock rod at 10 any desirable distance above the bottom of the tank, a trip rod 35 is provided and is slidably fitted in a guide opening 36 provided in the lower end. The upper end of the trip rod 35 carries a block 36 having a 15 pair of arms 37 which have openings in which the lock rod 30 is slidably fitted. A spring catch or latch 38 is provided and has one end fastened, as by means of a screw 39, to the block 36. The other end portion of 20 the spring latch or catch member 38 is disposed in between the arms 37 and by virtue of its inherent resiliency presses up against the lock rod 30. The lock rod 30 is provided at spaced intervals with notches 25 40 with which the catch 38 is selectively co-operable. The lower end of the trip rod 35 projects below the sampler and the extent to which it so projects may be regulated by sliding it along the lock rod and securing it 30 in adjusted position thereon by engaging its latch 38 with the selective notch 40. When the trip rod strikes the bottom of the tank it moves the lock rod 30 upwardly against the action of the coil spring 33 and disengages the lower end of the lock rod from 35 the lug 17; thereby permitting the spring 23 to swing the closure plate 12 to closed position.

A bail 50 is connected with the upper 40 head or end piece 4 and has an eye 51 to facilitate its attachment to a lowering line chain or catch pole, said bail constituting with said chain or line means for lowering the sampling device. In the construction 45 illustrated one arm of the bail 50 has a trunnion 52 which is engaged in a bearing 53 provided on the upper end piece 4. The other arm of the bail has an extension 54 provided with an opening 55 receiving the 50 outturned upper end 56 of the lock rod. A cotter pin 57 prevents displacement of the outturned ends 56 of the lock rod 30 from the opening 55 of the extension 54 of the bail. This arrangement permits the lowering 55 line to be jerked to disengage the lock rod from the lug 17 and permit swinging of the closure plate 12 to closed position.

In the use of the device the closure plate 12 is swung to open position and is held in 60 such position by the lock rod 30. The device is then lowered into the oil and the oil passes in through the openings 11 and out through the upper open end until the sampler is in the region where it is to take a sample. 65 The closure plate is then closed by jerking

the lowering line to cause the bail 50 to ride the lock rod upwardly and disengage it from the lug 17 of the closure plate or by virtue of the engagement of the lower end of the trip rod 35 with the bottom of the 70 tank and the upward thrust which such engagement exerts on the lock rod. When the closure plate swings to closed position its lugs 18 are engaged with the screws 6 to hold the plate in such position. 75

We claim:

1. A sampler of the character described comprising a body having open ends, a closure for one of the open ends, means for biasing the closure to closed position, means for holding the closure in open position, and lowering means connected with said last mentioned means and adapted to be operated to release the same. 80

2. A sampler of the character described including a body having open ends, a closure for one of the ends, said closure having an integral projection, means for biasing the closure to closed position, a slidable spring pressed lock rod directly engageable with the integral projection of the closure for holding the closure in open position, and means for disengaging said lock rod from the closure. 85

3. A sampler of the character described including a body having open ends, a closure for one of the ends, means for biasing the closure to closed position, a spring pressed lock rod for holding the closure in open position, and means for disengaging said lock rod from the closure and including a bail connected with the lock rod and adapted to be connected with the lowering means. 90

4. A sampler of the character described including a body having open ends, a closure for one of the ends, said closure having an integral projection, means for biasing the closure to closed position, a slidable spring pressed lock rod directly engageable with the integral projection of the closure for holding the closure to open position, means for disengaging said lock rod from the closure and including a trip rod engageable with the bottom of the tank, an adjustable connection between the trip rod and the lock rod including a block slidably mounted on the lock rod, and releasable interengaging means between the block and the lock rod. 110 115

5. A sampler of the character described including a body having open ends, a closure for one of the ends, means for biasing the closure to closed position, a spring pressed lock rod for holding the closure to open position, means for disengaging said lock rod from the closure and including a trip rod engageable with the bottom of the tank, an adjustable connection between the trip rod and the lock rod including a block 120 125

slidably mounted on the lock rod, and releasable interengaging means between the block and the lock rod and consisting of a spring-pressed latch member mounted on 5 the block, said lock rod having a plurality of notches with which the latch member is selectively engageable.

6. In a sampler, a body including a cylinder, end pieces connected with the cylinder, guard plates fastened to the end pieces and protecting the same, one of the end plates having an unobstructed opening, the other end plate having a plurality of openings and a rotatable closure for said other 10 end plate including a hub pivotally mounted on such end plate, closure elements carried by the hub, and a peripheral ring connecting the closure elements, spring means for urging the closure plate to closed position, and means for releasably securing the closure plate in open position and including a lock 15 rod slidably mounted on the body and engageable with one of the lugs.

7. In a sampler, a body including a cylinder, end pieces connected with the cylinder, 20 guard plates fastened to the end pieces and protecting the same, one of the end plates having an unobstructed opening, the other end plate having a plurality of openings and a rotatable closure for said other end 25 plate including a hub pivotally mounted on such end plate, closure elements carried by the hub, a peripheral ring connecting the closure elements, spring means for urging the closure plate to closed position, and 30 means for releasably securing the closure plate in open position and including a lock rod slidably mounted on the body and engageable with one of the lugs.
